J. DAUBEK.

CURTAIN OR COVER.

No. 19,324.

Patented Oct. 1, 1889.

UNITED STATES PATENT OFFICE.

JOSEF DAUBEK, OF VIENNA, AUSTRIA-HUNGARY, ASSIGNOR TO MILLS & GIBB, OF NEW YORK, N. Y.

DESIGN FOR A CURTAIN OR COVER.

SPECIFICATION forming part of Design No. 19,324, dated October 1, 1889.

Application filed August 20, 1889. Serial No. 321,410. Term of patent 3½ years.

To all whom it may concern:

Be it known that I, JOSEF DAUBEK, of Vienna, Austria-Hungary, have invented a new and original Design for Curtains or Covers, of which the following is a specification, reference being had to the accompanying photograph, forming a portion thereof.

The leading features of the design consist, first, of a panel A, representing the end and side borders made up of a series of fancy floral and leaf-like figures *a* and *a'*; secondly, a plain field B, inclosed by the panel A, having drawn thereon a series of cornucopia-like figures *b*,

and, finally, a panel D, formed at one end of the field, representing an inserted or attached strip of fabric decorated with a cluster of fancy flowers *d* of the morning-glory type.

I claim—

A design for a curtain or cover, substantially as herein shown and described.

Vienna, August 1, 1889.

JOSEF DAUBEK.
